**EXPANSIBLE DRIVING CORE FOR DRIVING
PILE SHELLS**

Howard F. Caudill, Arlington Heights, Ill.

Application March 18, 1957, Serial No. 646,740

18 Claims. (Cl. 61—79)

The present invention relates to an expandable driving core for driving pile shells, and is primarily intended for the driving of tubular steel pile shells down into the ground through the operation of a pile driver. These pile shells are preferably of cylindrical or non-tapered form. After the pile shell has been driven down to the required depth, the expandable driving core is removed therefrom, following which the shell is filled with concrete, which may be reinforced by the addition of reinforcing rods or structural elements imbedded therein.

For reasons of economy it is frequently desirable to use relatively light gauge pile shells of cylindrical or non-tapered form which do not have sufficient wall thickness and sectional area to enable them to be driven down into the ground under the compression force of driving blows transmitted solely to their upper ends.

My improved expandable driving core is particularly intended for the driving of these relatively thin wall cylindrical pile shells, such being made possible by the action of the core expanding outwardly into high pressure binding engagement with the inner surface of the pile shell. Thereupon, the driving blows of the pile driving hammer are imparted primarily to the expanded driving core so that the core draws the pile shell down into the ground by a distributed application of the driving forces along the entire length of the shell, or along the major portion of its length. My improved driving core is applicable to the driving of either smooth wall pile shell, or helically corrugated shell, or cylindrically corrugated shell.

One of the principal objects of the invention is to provide an improved expandable core which has a very sturdy, shock-resisting arrangement of cams for effecting its expansion and contraction; as distinguished from prior pneumatic types of expandable cores which are expanded by pneumatic air pressure acting in an elastic expandable container extending lengthwise within the core; or as distinguished from pivoted link or pin and slot expansion actions.

More specifically in this regard, it is an object of the invention to provide an expandable driving core which will have an improved mechanical expanding action, and will also have an improved mechanical retracting action, both of which actions are attained by very sturdy, shock-resisting cams which can withstand the extremely heavy impact blows of the pile driving hammer. The inability to withstand the driving blows of the pile driving hammer has made most of these prior expandable cores of short life or impractical.

The positive cam type of mechanical retraction is a particular feature of the present invention because it insures that the core will positively retract to its original diameter under the action of hoisting pressure exerted upwardly through the stem of the core, as distinguished from gravitational and spring urged retraction which characterizes the prior pneumatic types of expandable cores. The non-positive gravitational and spring urged

2

retraction in many of these prior expandable cores frequently fails to free the core from the pile shell after the driving operation.

Another object of the invention is to provide an expandable driving core in which the major portion of the driving blows of the pile driving hammer is borne by the central stem of the core rather than by the expandable leaves.

Another object of the invention is to provide an expandable driving core which can be quickly and easily repaired in the event of damage arising as a result of the pile shell striking a boulder, rock ledge or other underground obstruction during the driving operation. My improved core is characterized by a unique construction and arrangement of expandable outer leaves, which permit a damaged leaf to be quickly and easily repaired or substituted. This repair or substitution of a damaged leaf can generally be effected while my improved core structure is suspended between the leads of the pile driving hammer. Thus, repair or substitution of a core leaf need not require that the pile driving operation be shut down for a substantial period.

Another object of the invention is to provide an expandable driving core which has few parts, is simple and inexpensive to construct, and which does not require a source of compressed air for its operation.

Other objects, features and advantages of the invention will appear from the following detailed description of certain preferred embodiments thereof. In the accompanying drawings illustrating such embodiments:

Figure 1 is a fragmentary vertical axial sectional view of one embodiment showing the expandable core or mandrel in its retracted condition, this view corresponding to a section taken on the plane of the line 1—1 of Figure 3.

Figure 2 is a similar view showing the mandrel expanded outwardly into the pile shell, corresponding to a section taken on the plane of the line 2—2 of Figure 4.

Figure 3 is a transverse sectional view taken on the plane of the line 3—3 of Figure 1, showing the core or mandrel in its retracted condition.

Figure 4 is a transverse sectional view taken on the plane of the line 4—4 of Fig. 2, showing the core or mandrel in its expanded condition.

Figure 5 is a transverse detail sectional view of the core head, taken on the plane of the line 5—5 of Figure 1.

Figure 6 is a fragmentary detailed sectional view showing the core provided with an outwardly projecting helical rib for engaging in the helical groove of a helically corrugated pile shell, and

Figure 7 is a fragmentary axial sectional view showing a stepped or multiple-diameter embodiment of my expandable core.

Referring first to Figures 1—5, my improved core structure is designated 16 in its entirety, and the pile shell which it is intended to drive is designated 17 in its entirety. The main elements of the improved core comprise an upper driving head 19, a depending central stem portion 20 made up of longitudinally extending radial fins 21, and a plurality of longitudinally extending outer leaves 22 of arcuate outer section.

The driving head 19 is preferably in the form of a forging or steel casting, having a cushion container 23 projecting upwardly from its upper surface. This container houses a cushioning block of wood, rubber, or other like cushioning material adapted to cushion the blows of the pile driving hammer striking the driving head 19. The underside of the driving head is formed with a cup-shaped cylindrical receptacle or socket 26 into which extends a cylindrical collar or head 28 which is anchored to the upper end of the central vertical stem

20. Formed in this upper collar 28 of the stem is an annular retaining groove 30. Projecting into this annular groove 30 are a plurality of keepers 32 which are removably mounted in horizontal slots 34 angularly spaced around the side walls of the driving head 19 (Figure 5). Projecting outwardly from the driving head 19 at the top and bottom edges of the slots 34 are apertured retainer lugs 36. Each retaining keeper 32 has an apertured outer portion 38 which is adapted to lie between the apertured lugs 36, and to receive a removable retainer bolt 40 which passes down through the apertures in the lugs 36 and in the keeper portions 38. Upon removal of the bolts 40 the keepers 32 may be withdrawn so as to permit upward removal of the driving head 19 from the core stem 20. Apertured hoisting lugs 42 project outwardly from the upper edge of the driving head 19 for enabling the driving head to be attached to the pile driving hammer through cables, chains, hooks or the like so that the head or the entire driving core can be lifted vertically by upward pull exerted on the pile driving hammer. The pile driving blows are transmitted downwardly from the driving head 19 to the core stem 20 through the inner abutment face 26' of the socket 26 and the upper abutment face 28' of the core collar 28. Attention is directed to the fact that the provision of the keepers 32 engaging in the annular groove 30 of the core collar establishes a swivel connection which permits horizontal turning rotation of the core stem 20 within the driving head 19. This swiveling connection permits the core stem 20 to rotate relatively to the driving head 19 when driving pile shells of the helically corrugated type, these latter pile shells imparting a substantial turning torque to the core stem during the driving operation.

Referring now to Figures 3 and 4 showing the construction of the core stem 20, it will be seen that it comprises three or more radially extending fin bars 21 which have their adjacent inner edges welded together at 46. These fin bars extend down the entire length of the driving core, having their upper ends welded or otherwise secured to the stem collar 28, and having their lower ends welded to a circular bottom closure cap 48. This closure cap or head 48 has an annular conical seating surface 48'.

Referring now to the outer leaves 22, there are as many of these leaves as there are radially extending fin bars 21, these leaves having vertically slidable mounting on the fin bars. The leaves consist of arcuate metallic plates which are preferably of a length substantially equal to the vertical length of their respective fins 21, and which have an outer radius of uniform cylindrical curvature from end to end corresponding substantially to the radius of the inner wall of the cylindrical pile shell 17 to be driven by the core. The angular span of each leaf is such that the leaves can be collapsed into the over-all retracted diameter shown in Figure 3, with a slight space still remaining between adjacent leaves. Detachably secured to the lower end of each leaf 22 is a sector shaped flange 49 which has an interior conical seating surface 49' adapted to coat with the exterior conical seating surface 48' of the closure head 48 when the core is expanded, as shown in Figure 2. The sector-shaped flanges 49 are detachably secured to the lower ends of the leaves 22 by bolts or the like 51 to permit separation of the flange from its respective leaf when it is desired to remove the leaf from the core structure for repair or replacement.

Referring now to the cam or wedge apparatus which mechanically extends and retracts the core leaves 22 relatively to the core stem 20, each radially extending fin or rib 21 is notched out at successive vertically spaced levels to form upper and lower inwardly extending radial shoulders 52 and 53, which are joined by the upwardly and outwardly sloping shoulders 54. Welded along each sloping shoulder 54 is a cam bar 55 which has its upper end terminating at the upper radial shoulder 52, and which has its lower end terminating at the lower radial

shoulder 53. This cam bar 55 is preferably of circular cross section, and the sloping shoulder 54 of each notch is preferably recessed in arcuate cross section to receive the circular inner surface of the cam bar 55.

Extending inwardly from each leaf 22 at each of the vertically spaced levels of the cam bars 55 is a cam follower 56, which is in the form of a horizontally extending plate of sector profile corresponding to the sector expanse of its respective leaf 22, as viewed in Figures 3 and 4. Each of these cam follower plates 56 is preferably welded along the outer edge to its respective leaf 22, although it will be understood that it might be otherwise secured thereto or might even be formed integral therewith. Cut down centrally from the inner apex of each of these cam follower plates is an outwardly extending slot 58 which terminates in a substantially circular hole 60. The side surfaces of each slot 58 embrace the side surfaces of the associated fin bar 21, and each circular hole 60 has sliding cam follower engagement with the associated circular cam bar 55. The coaction between the outside surface 55' of each cam bar 55 and the outer surface of the associated hole 60 establishes the cam relation that expands the leaves 22, and the coaction between the inside surface 55" of each cam bar and the inside surface of the associated hole 60 establishes the cam relation that retracts the leaves 22.

In Figure 1, the lower portion of the driving head 19 has been broken away to show the spaced relationship between the underside 28" of the core head 28 and the upper ends of the uppermost cam bars 55. This spaced relationship defines horizontal clearance spaces 62 extending radially outwardly between the underside 28" of the core head 28 and the upper ends of the adjacent cam bars 55, which clearance spaces are normally closed by the depending skirt portion of the driving head 19. By removing the keeper bars 32 and raising the driving head 19 relatively to the core head 28, the outer ends of these horizontal clearance spaces 62 can be opened. This permits the uppermost cam follower plate 56 of a damaged leaf 22 to be moved outwardly into a position clear of the upper end of the associated cam bar 55, whenever it is desired to remove a damaged leaf 22 for replacement or repair, as will be later described in greater detail.

The conventional tubular pile shell adapted to be driven by the above described expandible core is indicated generally at 17, this pile shell usually having a cup shaped driving boot 18 welded to its lower end. The expandible core 16 is lowered into the pile shell 17 when the core is in its completely retracted condition, with the expandible leaves 22 all hanging down in their lower inwardly retracted positions, as shown in Figures 1 and 3. The limit of lower inward movement of the leaves is defined either by the inner surfaces of the leaves striking the outer edges of the radially extending ribs 21, or by the under surfaces of the cam follower plates 56 striking the lower notching shoulders 53 cut into the ribs. In this retracted condition, the core is lowered into the shell, or the shell is drawn up over the core, until the arcuate base flanges 49 at the lower ends of the expandible leaves 22 strike the bottom of the shell boot 18. Thereupon, continued downward movement of the core stem 20 relatively to the expandible leaves 22 causes the cam bars 55 to exert an outward camming force on the cam follower plates 56 for forcing the expandible leaves 22 outwardly against the inner cylindrical wall of the pile shell 17. Substantially at the time that the leaves 22 reach the outer limits of their expansion movement within the pile shell, the bottom closure head 48 at the lower end of the core stem arrives substantially in seating engagement with the sector shaped flanges 49 at the lower ends of the leaves. Since substantially all of the driving energy of the pile driving hammer is transmitted to the pile shell 17 through the inclined cam bars 55 and cam followers 56, it follows that the expandible core will remain firmly locked within the pile shell from end to

end thereof during the entire driving operation. This insures a uniform distribution of the pile driving forces over the entire length of the pile, thereby permitting a thin wall pile shell to be used.

In the operation of withdrawing the driving core from the driven pile shell, a hoisting force is transmitted to the upper driving head 19 of the core through the apertured hoisting lugs 42. This slides the stem 20 and cam bars 55 upwardly within the cam follower plates 56, with the result that the inner cylindrical surfaces 55" of the cam bars exert a positive retracting force on the inner surfaces of the cam follower holes 58, thereby positively retracting the expansible leaves 22 inwardly to positions where they freely clear the inner wall surface of the pile shell. The expansible core is then withdrawn from the pile shell in the collapsed or retracted condition shown in Figures 1 and 3, and is in immediate readiness for insertion into another pile shell.

To effect the removal of a damaged leaf 22 for replacement or repair, the entire driving core 16 is first hoisted into an elevated or above-ground position between the leads of the pile driver, the stem portion 20 of the driving core being held in this elevated position as by having its lower end blocked up on a suitable support. Following this, the sector shaped flange 49 at the lower end of the damaged leaf is removed; the keeper bars 32 are released; and the driving head 19 is then raised to open the outer ends of the clearance spaces 62 which, as previously described, are defined between the underside 28" of the core head 28 and the upper ends of the uppermost cam bars 55. The damaged leaf is then slid upwardly to bring its uppermost cam follower plate 56 into the open clearance space 62. This lifting of the leaf to bring the uppermost cam follower plate 56 into the clearance space 62, free of the uppermost cam bar 55, also brings each of the successively lower cam follower plates 56 into positions free of the upper ends of each of the respective lower cam bars 55. Thereupon, the damaged leaf is free to be removed laterally or outwardly from the stem portion 20 of the core. The replacement of the repaired leaf or of a new leaf is merely a reversal of the foregoing.

In Figures 3 and 4 I have shown the outer surfaces of the expansible leaves 22 as being provided with outwardly extending projections 70 adapted to make interlocking indentations 71 in the inner surfaces of smooth walled pile shells 17. These projections 70 are preferably in the form of small metallic cones or hemispheres which are welded to the outer surfaces of the leaves 22. The leaves 22 are expanded outwardly with sufficient force under the driving blows of the hammer to cause these projections 70 to create the interlocking indentations 71 in the wall of the pile shell, for establishing a more positive grip of the expansible core within the shell in the driving operation. These projections 70 clear themselves completely from the indentations 71 in the positive retraction of the expansible leaves. The projections 70 may be arranged in rows or in any other desired pattern on the outer surfaces of the leaves 22. However, a preferred arrangement is to arrange them helically about 8 or 10 inches apart along the line of the helix and with the helix having the helical pitch of helically welded smooth wall pile shell welded along a butt seam, a lap seam or a lock seam, so that the button-like projections 70 will not intersect the helically welded seam but will act on the shell wall between successive convolutions of the helically welded seam.

In Figure 6 I have shown a modified construction wherein the outer surfaces of the expansible leaves 22 are provided with segments 74 of an outwardly projecting helical rib for engaging in the helical groove 75 of a helically corrugated pile shell 17a. These helical rib segments 74 may consist of sections of half-round bar or other convex bar coiled as helical segments over the surfaces of the expansible leaves 22 and having their flat

surfaces welded to the leaves. Registration of the helical ribs 74 with the helical grooves 75 can be effected by causing slow relative rotation between the core and the pile shell in the act of expanding the core into the shell.

For driving pile shells of the type in which the corrugations extend circumferentially as distinguished from helically, the convex ribs 74 would be welded to the leaves 22 as circumferential segments instead of helical segments.

In Figure 7 I have shown a modified embodiment wherein my improved expansible core is of stepped or multiple-diameter construction, comprising upper and lower sections 16b, 16c of different diameters, for driving multiple-diameter pile shells 17b, 17c. The upper section 16d and the lower section 16c are both constructed identically to the single diameter section 16 shown in Figures 1-4, the only difference being that the lower section 16c is of smaller diameter than the upper section 16d, the stem 20 and the fin bars 21 being stepped down in size in the lower section. As illustrative of typical proportions which may be used, the upper section 16b may be constructed to drive twelve inch pile shells 17b, and the lower section 16c may be constructed to drive ten inch pile shells 17c. The adjacent ends of the upper and lower pile shells 17b, 17c may be joined together in any suitable manner, such as with an overlapping joint 80 provided with an intervening joint sleeve 81 welded to both the upper and lower shell sections.

While I have illustrated and described what I regard to be the preferred embodiments of my invention, nevertheless it will be understood that such are merely exemplary and that numerous modifications and rearrangements may be made therein without departing from the essence of the invention.

I claim:

1. In an expansible driving core for driving pile shells, the combination of an axially extending stem, a plurality of expansible leaves surrounding said stem, a plurality of vertically spaced cams on said stem for each leaf, and a plurality of cam followers on each leaf cooperating with said cams, said cams comprising inclined bars sloping upwardly and outwardly relatively to said stem, and said cam followers having holes embracing outer and inner surfaces of said cam bars, whereby relative axial motion between said stem and said leaves in one direction effects positive expansion of said leaves into engagement with the pile shell at the beginning of the driving operation, and whereby relative axial motion in the opposite direction effects positive retraction of said leaves out of engagement with the pile shell at the completion of the driving operation in the core retracting operation.

2. In an expansible driving core for driving pile shells, the combination of an axially extending stem comprising outwardly projecting fins, a plurality of longitudinally extending expansible leaves surrounding said stem, a plurality of vertically spaced cams on said fins for each leaf, and a plurality of cam follower sectors on each leaf cooperating with said cams, said cams comprising inclined bars sloping upwardly and outwardly along outer edges of said fins, said cam bars being of greater thickness than said fins to present outer and inner cam surfaces, said cam follower sectors comprising holes embracing said cam bars and engaging the outer and inner cam surfaces thereof, whereby downward motion of said stem within said leaves effects positive expansion of said leaves into engagement with the pile shell at the beginning of the driving operation, and whereby upward motion of said stem within said leaves effects positive retraction of said leaves out of engagement with the pile shell at the end of the driving operation.

3. In an expansible driving core for driving pile shells, the combination of an axially extending stem comprising outwardly projecting fins, a plurality of longitudinally extending expansible leaves surrounding said stem, a plurality of vertically spaced cams on said fins for each

leaf, and a plurality of cam follower sectors on each leaf cooperating with said cams, said cams comprising bars of round section sloping upwardly and outwardly along the outer edges of said fins, said round cam bars being of greater thickness than said fins to present outer and inner cam surfaces, said cam follower sectors having slots embracing said fins and having substantially round holes at the outer ends of said slots surrounding said cam bars and engaging the outer and inner cam surfaces thereof, whereby downward movement of said stem within said leaves effects positive expansion of said leaves outwardly into engagement with the pile shell at the beginning of the driving operation, and whereby upward movement of said stem within said leaves effects positive retraction of said leaves out of engagement with the pile shell at the end of the driving operation.

4. In an expandable driving core for driving pile shells, the combination of an axially extending stem, a plurality of expandable leaves surrounding said stem, a plurality of vertically spaced cams on said stem for each leaf, a plurality of cam followers on each leaf cooperating with said cams, said cams comprising inclined bars sloping upwardly and outwardly relatively to said stem, and said cam followers having holes embracing outer and inner surfaces of said cam bars, whereby relative axial motion between said stem and said leaves in one direction effects positive expansion of said leaves into engagement with the pile shell at the beginning of the driving operation, and whereby relative axial motion in the opposite direction effects positive retraction of said leaves out of engagement with the pile shell in the core retracting operation, and protuberances on said leaves adapted to effect a locking fit with the interior of said pile shell in the pile driving operation.

5. In an expandable driving core for driving pile shells, the combination of an axially extending stem comprising outwardly projecting fins, a plurality of longitudinally extending expandable leaves surrounding said stem, a plurality of vertically spaced cams on said fins for each leaf, and a plurality of cam follower sectors on each leaf cooperating with said cams, said cams comprising inclined bars sloping upwardly and outwardly along outer edges of said fins, said cam bars being of greater thickness than said fins to present outer and inner cam surfaces, said cam follower sectors comprising holes embracing said cam bars and engaging the inner and outer cam surfaces thereof, whereby downward motion of said stem within said leaves effects positive expansion of said leaves into engagement with the pile shell at the beginning of the driving operation, and whereby upward motion of said stem within said leaves effects positive retraction of said leaves out of engagement with the pile shell at the end of the driving operation, and spaced protuberances projecting outwardly from said leaves adapted to make indentations in the inner wall of said pile shell in the operation of driving the shell.

6. In an expandable driving core for driving corrugated pile shells, the combination of an axially extending stem, a plurality of expandable leaves surrounding said stem, ribs projecting outwardly from said leaves for interfitting with the corrugations in said corrugated pile shell, a plurality of vertically spaced cams on said stem for each leaf, and a plurality of cam followers on each leaf, cooperating with said cams, said cams comprising inclined bars sloping upwardly and outwardly relatively to said stem, and said cam followers having holes embracing inner and outer surfaces of said cam bars, whereby relative axial motion between said stem and said leaves in one direction effects positive expansion of said leaves into engagement with the pile shell at the beginning of the driving operation, and whereby relative axial motion in the opposite direction effects positive retraction of said leaves out of engagement with the pile shell in the core retracting operation.

7. In an expandable driving core for driving spirally

corrugated pile shells, the combination of an axially extending stem comprising outwardly projecting fins, a plurality of longitudinally extending expandable leaves surrounding said stem, sector shaped ribs projecting outwardly from said leaves in a spiral pattern for interfitting with the spiral corrugations in said shell, a plurality of vertically spaced cams on said fins for each leaf, and a plurality of cam follower sectors on each leaf cooperating with said cams, said cams comprising inclined bars sloping upwardly and outwardly along outer edges of said fins, said cam bars being of greater thickness than said fins to present outer and inner cam surfaces, said cam follower sectors comprising holes embracing said cam bars and engaging the outer and inner cam surfaces thereof, whereby downward motion of said stem within said leaves effects positive expansion of said leaves into engagement with the pile shell at the beginning of the driving operation, and whereby upward motion of said stem within said leaves effects positive retraction of said leaves out of engagement with the pile shell at the end of the driving operation.

8. In an expandable driving core for driving pile shells, the combination of an axially extending stem, a plurality of expandable leaves surrounding said stem, a plurality of vertically spaced cams on said stem for each leaf, and a plurality of cam followers on each leaf cooperating with said cams, said cams comprising inclined bars sloping upwardly and outwardly relatively to said stem, and said cam followers having holes embracing outer and inner surfaces of said cam bars, whereby relative axial motion between said stem and said leaves in one direction effects positive expansion of said leaves into engagement with the pile shell at the beginning of the driving operation, and whereby relative axial motion in the opposite direction effects positive retraction of said leaves out of engagement with the pile shell in the core retracting operation, a driving head at the upper end of said stem, and a swivel connection between said stem and said driving head permitting relative rotation between said stem and said driving head in the driving operation.

9. In an expandable driving core for driving pile shells, the combination of an axially extending stem, a driving head at the upper end of said core adapted to receive the driving blows of the pile driving hammer, a swivel collar on the upper end of said stem rotatably engaging in a recess in said driving head, said swivel collar having an undercut annular shoulder, releasable retainer means carried by said head and adapted to releasably engage under said undercut shoulder for releasably holding said swivel collar for rotative movement in said driving head, a plurality of expandable leaves surrounding said stem, a plurality of vertically spaced cams on said stem for each leaf, and a plurality of cam followers on each leaf cooperating with said cams, said cams comprising inclined bars sloping upwardly and outwardly relatively to said stem, and said cam followers having holes embracing outer and inner surfaces of said cam bars, whereby relative axial motion between said stem and said leaves in one direction effects positive expansion of said leaves into engagement with the pile shell at the beginning of the driving operation, and whereby relative axial motion in the opposite direction effects positive retraction of said leaves out of engagement with the pile shell in the core retracting operation.

10. In an expandable driving core for driving pile shells, the combination of an axially extending stem, a plurality of expandable leaves surrounding said stem, a plurality of vertically spaced cams on said stem for each leaf, a plurality of cam followers on each leaf cooperating with said cams, said cams comprising inclined bars sloping upwardly and outwardly relatively to said stem, said cam followers having holes embracing outer and inner surfaces of said cam bars, said leaves defining a substantially circular opening at the lower end of said core, and a closure head on the lower end of said stem

adapted substantially to close said substantially circular opening in the operation of driving the pile shell.

11. In apparatus of the class described, the combination of pile shell means comprising an upper pile section of relatively large diameter, a lower pile section of relatively small diameter, a stepped multiple diameter expansible driving core for driving said pile shell means, said driving core comprising an upper core section of relatively large diameter for fitting within said upper pile section and a lower core section of relatively small diameter for fitting within said lower pile section, an axially extending stem within both core sections, each of said core sections comprising a plurality of expansible leaves surrounding said stem, a plurality of vertically spaced cams on said stem for each leaf, and a plurality of cam followers on each leaf cooperating with said cams, said cams comprising inclined bars sloping upwardly and outwardly relatively to said stem, and said cam followers having holes embracing outer and inner surfaces of said cam bars.

12. In apparatus of the class described, the combination of pile shell means comprising an upper pile section of relatively large diameter and a lower pile section of relatively small diameter, both pile sections being cylindrical from end to end, a stepped multiple diameter expansible driving core for driving said pile shell means, said driving core comprising an upper core section of relatively large diameter fitting within said upper pile section and a lower core section of relatively small diameter fitting within said lower pile section, both said upper and lower core sections being cylindrical from end to end, a stem extending axially down through said upper and lower core sections, said stem comprising outwardly projecting fins, each of said upper and lower core sections comprising a plurality of longitudinally extending expansible leaves surrounding said stem, a plurality of vertically spaced cams on said fins for each leaf, and a plurality of cam follower sectors on each leaf cooperating with said cams, said cams comprising inclined bars sloping upwardly and outwardly along outer edges of said fins, said cam bars being of greater thickness than said fins to present outer and inner cam surfaces, said cam follower sectors comprising holes embracing said cam bars and engaging the outer and inner cam surfaces thereof, whereby downward motion of said stem within said leaves effects positive expansion of said leaves into engagement with said upper and lower pile sections at the beginning of the driving operation, and whereby upward motion of said stem within said leaves effects positive retraction of said leaves out of engagement with said upper and lower pile sections, at the end of the driving operation.

13. In an expansible driving core for driving pile shells, the combination of an axially extending stem, a plurality of expansible leaves surrounding said stem, a plurality of vertically spaced cams on said stem for each leaf, a plurality of cam followers on each leaf cooperating with said cams, said cams comprising inclined bars sloping upwardly and outwardly relatively to said stem, said cam followers having holes embracing inner and outer surfaces of said cam bars, sector shaped flanges secured to the lower ends of said leaves defining a substantially circular opening at the lower end of said core, a closure head on the lower end of said stem adapted substantially to close said substantially circular opening in the operation of driving the pile shell, and means for detachably securing said sector shaped flanges to said leaves to permit removal therefrom when substituting leaves.

14. In an expansible driving core for driving pile shells, the combination of an axially extending stem, a plurality of outwardly expansible leaves surrounding said stem, a plurality of vertically spaced cams on said stem for each leaf, and a plurality of cam followers on each leaf cooperating with said cams, said cams comprising inclined bars sloping upwardly and outwardly relatively to said stem.

to said stem, and said cam followers having holes embracing outer and inner surfaces of said cam bars, whereby relative axial motion between said stem and said leaves in one direction effects positive expansion of said leaves into engagement with the pile shell at the beginning of the driving operation, and whereby relative axial motion in the opposite direction effects inward retraction of said leaves out of engagement with the pile shell at the completion of the driving operation, said cam followers being slidable off the ends of said inclined cam bars, to permit ready removal of any one of said leaves from said core.

15. In an expansible driving core for driving pile shells, the combination of an axially extending stem, a plurality of outwardly expansible leaves surrounding said stem, a plurality of vertically spaced cams on said stem for each leaf, a plurality of cam followers on each leaf cooperating with said cams, said cams comprising inclined bars sloping upwardly and outwardly relatively to said stem, and said cam followers having holes embracing outer and inner surfaces of said cam bars, whereby relative axial motion between said stem and said leaves in one direction effects outward expansion of said leaves into engagement with the pile shell at the beginning of the driving operation, and whereby relative axial motion in the other direction effects inward retraction of said leaves out of engagement with the pile shell in the core retracting operation, sector shaped flanges at the lower ends of said leaves defining a substantially circular core, means for releasably securing said flanges to the lower ends of said leaves, and a closure head on the lower end of said stem adapted substantially to close said substantially circular opening in the operation of driving the pile shell, any one of said leaves being removable from said core by removing the sector shaped flange at its lower end and then sliding the leaf upwardly to disengage the cam followers of that particular leaf from the upper ends of the inclined cam bars associated with that leaf.

16. In an expansible driving core for driving pile shells, the combination of an axially extending stem, a driving head at the upper end of said core adapted to receive the driving blows of the pile driving hammer, a swivel collar on the upper end of said stem rotatably engaging in said driving head, a plurality of expansible leaves surrounding said stem, a plurality of vertically spaced cams on said stem for each leaf, and a plurality of cam followers on each leaf cooperating with said cams, said cams comprising inclined bars sloping upwardly and outwardly relatively to said stem, and said cam followers having holes embracing outer and inner surfaces of said cam bars, whereby relative axial motion between said stem and said leaves in one direction effects outward expansion of said leaves into engagement with pile shell at the beginning of the driving operation, and whereby relative axial motion in the opposite direction effects inward retraction of said leaves out of engagement with the pile shell in the core retracting operation, said leaves defining a substantially circular opening at the lower end of said core, and a closure head on the lower end of said stem adapted substantially to close said circular opening in the operation of driving the pile shell.

17. In an expansible driving core for driving pile shells, the combination of an axially extending stem, a driving head at the upper end of said core adapted to receive the driving blows of the pile driving hammer, a swivel collar on the upper end of said stem rotatably engaging in said driving head, a plurality of expansible leaves surrounding said stem, a plurality of vertically spaced cams on said stem for each leaf, and a plurality of cam followers on each leaf cooperating with said cams, said cams comprising inclined bars sloping upwardly and outwardly relatively to said stem, and said cam followers having holes embracing outer and inner surfaces of said cam bars, whereby relative axial motion between said stem and said leaves in one direction effects outward expansion of said leaves into engagement with pile shell

at the beginning of the driving operation, and whereby relative axial motion in the opposite direction effects inward retraction of said leaves out of engagement with the pile shell in the core retracting operation, said leaves defining a substantially circular opening at the lower end of said core, and a closure head on the lower end of said stem adapted substantially to close said circular opening in the operation of driving the pile shell, any one of said leaves being removable from said core for repairs or substitution by sliding the cam followers of that leaf upwardly beyond the upper ends of the inclined cam bars associated with that leaf.

18. In an expandible driving core for driving pile shells, the combination of an axially extending stem, a driving head at the upper end of said core adapted to receive the driving blows of the pile driving hammer, a swivel collar on the upper end of said stem rotatably engaging in a recess in said driving head, said stem comprising outwardly projecting fins, a plurality of longitudinally extending expandible leaves surrounding said stem, a plurality of vertically spaced cams on said fins for each leaf, a plurality of cam follower sectors on each leaf cooperating with said cams, said cams comprising bars of round section sloping upwardly and outwardly along the outer edges of said fins, said round cam bars being of

greater thickness than said fins to present outer and inner cam surfaces, said cam follower sectors having slots embracing said fins and having substantially round holes at the outer ends of said slots surrounding said cam bars and engaging the outer and inner cam surfaces thereof, whereby downward movement of said stem within said leaves effects positive expansion of said leaves outwardly into engagement with the pile shell at the beginning of the driving operation, and whereby upward movement of said stem within said leaves effects positive retraction of said leaves out of engagement with the pile shell at the end of the driving operation, sector shaped flanges at the lower ends of said leaves defining a substantially circular opening at the lower end of said core, means releasably securing said sector shaped flanges to said leaves, and a closure head on the lower end of said stem adapted substantially to close said circular opening in the operation of driving the pile shell, any one of said leaves being removable from said core by releasing said sector shaped flange therefrom and sliding said leaf upwardly until the cam followers thereof clear the upper ends of the inclined cam bars associated with that leaf.
